(57) **CLAIM**

The ornamental design for a pacifier, as shown and described.

DESCRIPTION

FIG. 1 is a perspective view of the new pacifier;

FIG. 2 is a front plan view thereof;

FIG. 3 is a first side plan view thereof;

FIG. 4 is a top end view thereof;

FIG. 5 is a bottom end view thereof; and,

FIG. 6 is a back end view thereof.

The broken line showing is for illustrative purposes only and forms no part of the claimed design.
